UNITED STATES PATENT OFFICE.

CLARENCE W. SPAULDING, OF MUSKEGON HEIGHTS, MICHIGAN.

MITER-BOX.

1,301,519.

Specification of Letters Patent. Patented Apr. 22, 1919.

Application filed October 2, 1915. Serial No. 53,841.

To all whom it may concern:

Be it known that I, CLARENCE WASHINGTON SPAULDING, a citizen of the United States, residing at Muskegon Heights, in the county 5 of Muskegon and State of Michigan, have invented certain new and useful Improvements in Miter-Boxes; and I do hereby declare the following to be a full, clear, and exact description of the invention, such as 10 will enable others skilled in the art to which it appertains to make and use the same.

This invention relates to a miter-box, and has for its object to provide a device of this character including a minimum number of 15 parts so constructed and arranged as to be quickly and conveniently detachable or foldable for transportation.

Another object of the invention is the provision of a device of this character embodying 20 a novel form of saw support having movement either on a horizontal axis or a vertical axis.

Another object is the provision of means for automatically locking the saw support 25 in vertical position.

With these and other objects in view, the invention consists in the novel construction, arrangement and formation of parts as will be hereinafter specifically described, claimed 30 and illustrated in the accompanying drawings, in which,

Figure 1 represents a top plan view of the miter-box,

Fig. 2 represents a transverse sectional 35 view partly broken away, on the line 2—2 of Fig. 1,

Fig. 3 represents a rear elevation of the miter-box, partly broken away,

Fig. 4 represents a transverse sectional 40 view through the device, showing in detail the support and automatic locking device for the saw support, and

Fig. 5 is a section taken on the vertical plane indicated by the line 5—5 of Fig. 1.

Referring to the drawing in detail, wherein similar reference numerals designate corresponding parts throughout the several views, the numeral 10 indicates supporting legs formed integral with a frame structure over which is secured the bottom board 50 11. A back 12 is removably secured to the back bar 10^a of the frame structure by screws or winged nuts 13.

The saw supporting or the guiding frame 55 is supported by a block 14 having a longitudinal bore 15 and a downwardly project-

ing threaded shank 16 positioned through an opening formed in a horizontal bracket arm 10^b and secured in operative position thereon by a nut 17 threaded on said shank. 60 The bracket arm 10^b projects inwardly from the back bar 10^a. A shaft 18 is rotatably mounted within the bore 15 of the block 14 and extends a distance outwardly of the sides of the bottom 11, the extreme ends of 65 said shaft carrying blocks 19. A vertical groove 20 intersecting the bore 15 is formed through one end of block 14, and is adapted to receive a locking pin 21 secured to the shaft 18 for automatically locking the shaft 70 18 when the blocks 19 assume a horizontal position. A spring 22 is coiled around the shaft 18 and disposed between the block 14 and one of the blocks 19, and effects the automatic seating of the pin 21 in the groove 75 20 when said pin is moved to a vertical position by the shaft 18. A quadrant 23 which has its upper surface graduated as shown in Fig. 1 of the drawings and which is curved concentrically with the pivotal axis of the 80 block 14, is formed integral with the front bar 10^c of the frame 10^a and arranged under the shaft 18 for supporting and bracing the latter. The base 25 of a U-shaped member formed with parallel arms 26 is arranged 85 on the quadrant 23, and the arms 26 are centrally apertured to receive the shaft 18. A shaft 27 is rotatably journaled in the member 25 and is formed with a cam face 28 adapted to engage the lower outer edge of 90 the quadrant 23 when the handle 29 is rotated in one direction so as to clamp the member 25 rigid with the quadrant 23.

A pair of standards 30 is secured to each block 19. The standards extend vertically 95 and slidably receive the saw guides and supports 31 formed with vertical slots 32 to receive the saw. The upper ends of each pair of standards 30 adjustably receive a block 33 provided with a set screw 34 by 100 means of which said blocks are secured against accidental movement on the standards 30. A connecting bar 35 is secured to and between the blocks 33 for securing the upper ends of the standards 30 against relative movements. 105

A pair of arms 36 are pivotally connected at 37 to the rear face of the back 12 on opposite sides of the saw receiving opening 38 in the latter. Each arm 36 is provided with 110 a slot 40 which is curved concentrically with the pivotal axis 37 of the arm and which

receives the winged nut 39 to lock the arm in various adjusted positions. The arms 36 are adapted to support the saw carrying frame when cutting at various vertical angles. To permit of the accurate and quick adjustment of the arms 36 the rear side of the back 12 is graduated on both sides of the saw receiving openings 38 as illustrated in Fig. 3 of the drawings. The back bar 10^a 10 and the front bar 10^c are provided with openings to permit the saw carrying frame to be swung about its vertical axis 16.

In operation, the shaft 18 is released by rotating the handle 29 to disengage the cam 28 from the quadrant 23; the shaft 18 and coöperating parts are then swung to the proper angle on the pivotal axis 16 of the block 14. The frame is subsequently locked in adjusted position by turning the handle 29 to engage the cam face 28 of the shaft 27 against the quadrant 23. If desired, the shaft 18 may be moved longitudinally to disengage the pin 21 from the groove 20 and the shaft 18 rotated to tilt the guides 31 and saw to any desired position. In this adjustment, one of the pivoted arms 36 is adjusted to be engaged by rod 35 to support the saw at the desired angle. It will be understood that when the shaft 18 is rotated to move the pin 21 to a vertical position, the spring 22 automatically actuates the shaft 18 to seat the pin 21 in the groove 20 and thus lock the saw frame in a vertical position.

What I claim is:—

1. A miter box including a base, a back, a pivoted supporting block, a shaft rotatably and slidably mounted in said block, rods carried by the ends of the shaft, saw guides and supports carried by said rods, a bar located between and adjustably secured to said rods, an arm pivotally secured at its lower end to said back on each side of said shaft, means adapted to secure said arms in various angular positions with relation to the vertical, said arms being adapted to co-operate with the bar to support the bar in various angular positions with relation to the vertical, means by which said block may be secured against movement, and means by which the shaft may be held against rotation with relation to said block. 45

2. A miter box including a quadrant, a U-shaped member straddling said quadrant and having alining openings in the arms thereof at a point above said quadrant, a locking cam carried by said member and adapted to be moved into and out of engagement with the lower outer edge of the quadrant, and a shaft slidably and rotatably mounted in the openings of said member. 55

In testimony whereof I affix my signature in presence of two witnesses.

CLARENCE W. SPAULDING.
